US00D873264S

(12) **United States Design Patent** (10) **Patent No.:** **US D873,264 S**
(45) **Date of Patent:** **** Jan. 21, 2020**

(54) **ELECTRONIC DEVICE**

(71) Applicant: **Apple Inc.**, Cupertino, CA (US)

(72) Inventors: **Jody Akana**, San Francisco, CA (US); **Bartley K. Andre**, Palo Alto, CA (US); **Shota Aoyagi**, San Francisco, CA (US); **Anthony Michael Ashcroft**, San Francisco, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Matthew Dean Rohrbach**, San Francisco, CA (US); **Peter Russell-Clarke**, San Francisco, CA (US); **Benjamin Andrew Shaffer**, San Jose, CA (US); **Mikael Silvanto**, San Francisco, CA (US); **Christopher J. Stringer**, Woodside, CA (US); **Eugene Antony Whang**, San Francisco, CA (US); **Rico Zörkendörfer**, San Francisco, CA (US)

(73) Assignee: **Apple Inc.**, Cupertino, CA (US)

(**) Term: **15 Years**

(21) Appl. No.: **29/649,601**

(22) Filed: **May 31, 2018**

Related U.S. Application Data

(63) Continuation of application No. 29/599,234, filed on Mar. 31, 2017, now abandoned, which is a (Continued)

(57) **CLAIM**

The ornamental design for an electronic device, as shown and described.

DESCRIPTION

FIG. 1 is a top front perspective view of an electronic device showing our new design;

FIG. 2 is a top view thereof; and,

FIG. 3 is an enlarged view of the portion encircled in FIG. 2.

The dashed broken lines illustrate portions of the electronic device which form no part of the claimed design.

1 Claim, 2 Drawing Sheets

Related U.S. Application Data

continuation of application No. 29/519,731, filed on Mar. 6, 2015, now Pat. No. Des. 787,500.

The ornamental design for an electronic device, as shown and described.

DESCRIPTION

FIG. 1 is a top front perspective view of an electronic device showing our new design;

FIG. 2 is a top view thereof; and,

FIG. 3 is an enlarged view of the portion encircled in FIG. 2.

The dashed broken lines illustrate portions of the electronic device which form no part of the claimed design.
